(57) **CLAIM**

The ornamental design for a document camera as shown and described.

DESCRIPTION

FIG. 1 is a front, left and top perspective view of a document camera, showing my new design.

FIG. 2 is a rear, right and bottom perspective view thereof.

FIG. 3 is a front, left and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is another front, left and top perspective view thereof, shown in a folded state.

FIG. 11 is an enlarged view thereof, taken from encircled portion labeled “11” in FIG. 1.

FIG. 12 is an enlarged view thereof, taken from encircled portion labeled “12” in FIG. 1.

FIG. 13 is an enlarged view thereof, taken from encircled portion labeled “13” in FIG. 3.

FIG. 14 is an enlarged view thereof, taken from encircled portion labeled “14” in FIG. 3.

FIG. 15 is an enlarged view thereof, taken from encircled portion labeled “15” in FIG. 3.

FIG. 16 is an enlarged view thereof, taken from encircled portion labeled “16” in FIG. 3.

FIG. 17 is an enlarged view thereof, taken from encircled portion labeled “17” in FIG. 8; and,

FIG. 18 is an enlarged view thereof, taken from encircled portion labeled “18” in FIG. 8.

The dashed broken lines depict portions of the document camera that form no part of the claimed design. The dot-dash broken lines in FIGS. 1, 3, 8, and 11-18 depict the boundaries of the enlargements and form no part of the claimed design.

1 Claim, 18 Drawing Sheets
